UNITED STATES PATENT OFFICE.

ELI MAYNARD LONG, OF GENEVA, NEW YORK, ASSIGNOR, BY MESNE ASSIGNMENTS, TO THE STANDARD OPTICAL COMPANY, OF GENEVA, NEW YORK, INCORPORATED IN NEW YORK IN 1924.

LENS GRINDING AND POLISHING MACHINE.

Application filed August 2, 1921. Serial No. 489,197.

To all whom it may concern:

Be it known that I, ELI M. LONG, a citizen of the United States, residing at Geneva, in the county of Ontario, in the State of New York, have invented new and useful Improvements in Lens Grinding and Polishing Machines, of which the following, taken in connection with the accompanying drawings, is a full, clear, and exact 10 description.

This invention relates to a machine for grinding and polishing the surfaces of lenses in which the lens is caused to traverse the surface of a rotary grinding or polishing lap to impart the desired surface contour to the lens, and refers more particularly to the driving mechanisms for the lap and lens-holding device and to the means for adjusting the lens-holder and holding it 20 in its adjusted position.

In machines of this character in which fine emery, rouge and analogous materials are employed as the abrasive element, it is necessary to guard against the entrance of 25 those materials into the bearings of the movable parts to avoid excessive wear of the bearings, and while one of the objects is to enclose practically all of the working parts exclusive of the lap and lens-block in a 30 dust-proof housing or housings, the main object is to increase the general working efficiency and durability of the machine.

One of the specific objects is to provide means whereby the lens-holding device may 35 be easily and quickly adjusted to different angles relatively to the axis of the rotary lap.

Another object is to provide simple and efficient means whereby the lens-holder may 40 be reciprocated with a swinging oscillatory motion across the face of the lap with varying degrees of throw or arcs of movement.

Another object is to enable the arc of movement of the lens-holder to be changed 45 at will while the machine is in action.

A further object is to enable the supporting bracket for the lens-holding device to be adjusted transversely and to different angles relatively to the axis of the lap and

held in both positions of adjustment by 50 the operation of a single handpiece.

Other objects and uses relating to specific parts of the device will be brought out in the following description:

In the drawings:

Fig. 1 is a top plan of a machine embodying the various features of my invention, the table being partly broken away.

Fig. 2 is a front elevation of the same machine showing parts of the tray broken 60 away to disclose the interior mechanism.

Fig. 3 is a transverse vertical sectional view of the same machine taken on line 3—3 Fig. 1.

Fig. 4 is a horizontal sectional view 65 taken in the plane of line 4—4, Fig. 2.

Fig. 5 is a horizontal sectional view taken in the plane of line 5—5, Fig. 2 except that the outer ends of the clutch levers are broken away and the frame of the machine 70 omitted.

Fig. 6 is a detail vertical sectional view taken in the plane of line 6—6, Fig. 4.

Fig. 7 is a detail horizontal sectional view taken in the plane of line 7—7, Fig. 3 75 showing the means for varying the throw of the lens-holder.

Fig. 8 is a detail horizontal sectional view taken in the plane of line 8—8, Fig. 3.

Fig. 9 is a vertical sectional view of the 80 device for reciprocating the lens-holder with the operating pin at an angle to its rock-shaft.

Fig. 10 is a detail vertical sectional view taken on line 10—10, Fig. 1.

Fig. 11 is an enlarged detail sectional view taken on line 11—11, Fig. 2.

As illustrated this machine comprises the main supporting table —1—, a relatively stationary housing —2— and a waste receptacle —3— secured, respectively, by bolts —4— against the lower and upper faces of the table —1— for receiving and enclosing the major portion of the mechanisms for controlling the operations of a rotary lap 95 —5—, a lens-holder —6— movable across the upper surface of the lap —5—, a relatively stationary post —7— mounted on the table

at one side of the waste container, a clamping yoke —8— mounted upon the post for rotary adjustment, a sectional bracket —9— mounted on the yoke —8— for rotary adjustment about a horizontal axis, and mechanism for reciprocating the lens-holder across the upper face of the lap and for permitting the adjustment of the lens-holding device to different angles relatively to the axis 10 of the lap as will be hereinafter more fully explained.

The housing —2— comprises lower and upper sections —10— and —11— rigidly but detachably secured together end to end by 15 bolts —12—, the upper section being provided with laterally projecting apertured lugs —13— for receiving the clamping bolts —4— by which the housing is rigidly secured to the table —1—.

20 The front portion of the lower section —10— is substantially semi-circular about a vertical axis, while the rear portion is offset rearwardly and is substantially semi-circular about a horizontal axis for receiving and 25 supporting portions of the driving mechanism for the rotary lap —5—, the bottom of the housing section —10— being provided with an upstanding hub —10'— coaxial with said axis for receiving the lower end of an 30 upright shaft which also forms a part of the driving mechanism of the lap as will be hereinafter more fully explained.

The upper end of the section —10— is provided with a circular opening registering 35 with a similar opening in the lower end of the upper section —11—, the securing of the two sections together by the bolts —12— serving to produce a dust-proof housing for the interior mechanism and also forms a 40 reservoir for lubricating oil to the movable parts within the housing.

The upper end of the housing section —11— is reduced in diameter to form a circular hollow hub —14—, which extends 45 vertically through an opening —15— in the table —1— and some distance above the upper surface thereof where it is covered by a cap —16— telescoping therewith and around the outside thereof to prevent the entrance 50 of dust or other waste material from grinding into the bearings of the movable parts within the housing.

The waste receptacle —3— is clamped by the bolts —4— to the upper surface of the 55 table —1— concentric with and around the axis of the tubular hub —14— on the upper end of the housing —2— and is provided with a central up-turned annular flange —17— surrounding the lower portion of the 60 cap —16—, which in turn is provided with a down-turned marginal flange —18— covering and surrounding the upper end of the hub —17— directly below the lap —5— and also below the horizontal plane of the upper

edge of rim of the receptacle —3— to deflect 65 any waste material resulting from grinding the lens into said receptacle.

Lap operating means.

A counter shaft —19— is rotatably 70 mounted in a horizontal position in suitable bearings —20— at opposite sides of the rearwardly projecting offset of the lower housing section —10— and is provided with an external pulley —21— adapted to be connected by a belt to any available source of power (not shown) for rotating said shaft.

A vertical shaft —22— is journaled at its lower end in the hub —10'— and extends upwardly through the hub —14— and cap —16— coaxial therewith, said hub —14— being provided with an internal bushing —23— in which the adjacent portion of the shaft is journaled.

This bushing is held against axial and rotary movement by means of a set-screw —24— passing through an opening in the adjacent side of the hub —14—, the opposite side of said bushing being provided with a lengthwise groove —26— communicating 90 with an annular groove —27— in the upper end of the bushing whereby oil may be conducted to the interior of the bushing for lubricating the shaft —22—.

The upper portion of the shaft just above the upper end of the bushing —23— is provided with annular shoulders —28— against which the cap —16— normally rests.

The shaft —22— is also provided with a reduced threaded upper end —29— projecting above the upper face of the cap 16 and engaged by a nut —30— having a longitudinally tapered outer face upon which the lap —5— having a similar tapered socket is frictionally fitted to rotate with the shaft —22—, it being understood that the nut —30— serves to clamp the cap —16— against the shoulders —28— on said shaft to cause the cap to rotate therewith and thereby to assist in throwing any dust or foreign matter which may lodge on the cap into the receptacle by centrifugal force.

A rotary clutch member —31— is loosely mounted upon the upright shaft —22— and is provided at its lower end with a spiral gear —32— meshing with a similar spiral gear —33— which is secured to the counter-shaft —19— within the housing-section —10— as shown in Fig. 3 to impart relatively high speed rotary motion to the lamp —5—, the upper end of said clutch section being provided with an inner annular friction face —34— of relatively larger diameter than that of the gear —32—. The clutch-section —31— is somewhat conical and arranged with its larger end uppermost, the lower end together with the gear —32— being stepped upon ball-bearings —35— on

the upper end of the hub —10— to resist downward thrust of those parts without excessive friction.

Another clutch section —36— is keyed by 5 a pin —37— to the upright shaft —22— and engages the upper end of the loose clutch-section —31—, thereby holding the loose clutch-section against upward displacement relatively to the shaft and at the same time 10 permitting it to rotate continuously while the upright shaft with the section —36— and lap thereon remain at rest.

A series of, in this instance four, clutch levers —37— are pivoted at —38— to the 15 upper marginal edge of the cup-shaped clutch section —36— to rock vertically, and are provided with pendent lugs —39— movable into and out of engagement with the clutch face —34— of the section —31— as 20 the inner ends of the levers are rocked vertically in opposite directions.

The inner ends of the clutch levers —37— are pivotally connected by pins —40— to the lower end of a collar —41—, 25 which is slidable vertically along the shaft —22— between the clutch section —36— and lower end of the bushing —23— and therefore within the housing —2—, whereby the downward movement of said collar 30 —41— will force the lugs —39— into frictional engagement with the clutch section —31— to cause the latter to rotate with the shaft —22— while a reverse upward movement of said collar will release the lugs 35 —39— from the clutch section —31— to allow the upright shaft and lap carried thereby to remain at rest while the clutch section —31— continues to rotate through the medium of the gears —32— and —33—.

40 The means for reciprocating the collar —41— along the vertical shaft —22— comprises a forked lever —42— having its forked end spanning around the collar —41— and provided with rollers —43— en-

45 gaging in diametrically opposite sockets or slots —44— in said collar and its outer end secured to a rock-shaft —45— wholly within the housing —2—, said rock-shaft being journaled in a horizontal position in 50 a bearing —46— and extends to the exterior of said housing where it is provided with a crank-arm —47— having a split hub clamped by a screw —48— to said shaft to permit rotary adjustment when desired.

55 A lever —49— is pivoted at —50— to the crank-arm —47— and extends downwardly some distance therefrom and terminates in a forwardly projecting handle or knee engaging member —51— whereby it may be 60 rocked laterally about the pivot —50—.

A stud —52— is secured to the outer wall of the housing —2— some distance below the outer end of the rock-shaft —45— and is provided with a roller —53— adapted to 65 be engaged by a cam —54— on one side of

the lever —49— Fig. 2 for moving said lever upwardly when the cam is rocked against the periphery of the roller —53— and thereby elevating the inner end of the forked arm —42— and collar —41— to 70 effect the release of the lugs —39— from frictional engagement with the clutch face —34—, while on the other hand, the movement of the lever —49— away from the roller —53— allows the inner end of the 75 forked lever —42— and collar —41— to descend for frictionally engaging the lugs with the frictional face —34—. This latter movement is, however, aided by a series of, in this instance four, coil springs —55— 80 having their lower ends seated in sockets —56— in the upper end of the collar —41— and their upper ends engaged with a washer —57— which in turn rests against the lower end of the bushing —23— and is provided 85 with guide pins —58— projecting into the coil springs to assist in holding the collar against lateral turning movement.

That is, when the lever —49— is forced to its releasing position, the springs —55— 90 automatically force the collar —41— downwardly thereby operating the levers —37— to cause the lugs —39— to frictionally lock the clutch section —36— to the clutch section —31— and thereby to cause the rotation 95 of the shaft —22— with the lap thereon.

The pivotal connection —50— between the crank-arm —47— and lever —49— is normally some distance to one side of a direct line between the stud —52— and axis of the 100 rock-shaft —45—, while the lever —51— is provided with a concave seat —60— movable into and out of a direct line between the axes of the pivotal connection —50— and stud —52— so that when positioned in said line, it will automatically lock the crank-arm —47— and parts operated thereby in their clutch releasing positions against the actions of the springs —55—.

Lens-holder operating means.

A counter-shaft —61— is journaled in a horizontal position in suitable bearings beneath the table —1— adjacent the lower end of the tubular post —7— and therefore, some distance to the rear side of the housing —2—, and is provided with a pulley —62— adapted to be connected by a belt to the same source of power as that which drives the lap-operating mechanism, said shaft being provided with a spiral gear —63— meshing with a somewhat larger spiral gear —64— on the lower end of an upright shaft —65— to impart relatively slow speed rotary motion to said shaft which extends vertically through the tubular post —7—, the latter being secured by bolts —66— to the table —1— and has its lower end projecting through an opening in said table.

A yoke —67— is secured by a set-screw 130

—68— to the lower end of the post —7— and is provided with a journal bearing —69— for receiving and supporting the adjacent end of the shaft —61— and thereby holding its gear —63— in mesh with the gear —64.

The lower and upper ends of the upright shaft —65— are journaled in bushings —25— in the corresponding ends of the posts —7—, the upper end of said shaft being provided with a circular disk —70— which is secured to the shaft by means of an upstanding spindle —71— parallel with but eccentric to the axis of the shaft —65— and collar —70—, thereby serving as a key to lock said shaft disks to each other.

A hand piece —72— is journaled coaxially upon the spindle —71— and is provided with an offset cylindrical extension —73— which, however, is eccentric to the axis of said spindle and has its lower end normally resting upon the upper face of the disk —70— and provided with a downwardly projecting pin —74— adapted to enter any one of a series of, in this instance five, sockets —75— in the upper face of said disk, said sockets being arranged circumferentially about the axis of the spindle —71— and, therefore, eccentrically about the axis of the shaft —65—.

That is, the axis of the cylindrical hub —73— of the hand-piece —72— is offset from the axis of the spindle —71— approximately the same distance as the offset of the spindle from that of the shaft —65— so that when the hand-piece —72— is adjusted rotarily to one position, the axis of its cylindrical hub —73— will be substantially coincident with the axis of the shaft —65— but when adjusted from that position, the axis of the cylindrical portion —73— will be gradually moved away from the axis of the shaft until it reaches its maximum distance therefrom, the hand-piece with its cylindrical hub —73— being movable axially against the action of a retracting spring —77— to withdraw the pin from any one of the sockets —75— with which it may be registered, it being understood that the hand-piece will be automatically returned by said spring to cause its pin —74— to enter the registering socket to hold the hand-piece in its adjusted position.

55 A collar —78— is journaled upon the cylindrical hub —73— of the hand-piece —72— and is connected by a rod —79— and universal joint —80— to one end of a slide-rod —81— which is movable horizontally in a suitable guide-way —82— on the adjacent section of the bracket —9— which extends over the lap —5— when the machine is in operation.

The bracket —9— is composed of relatively movable sections —83— and —84—,

the section —83— being provided with a horizontally extending hub —85— journaled in a suitable bearing —86— on the upper section of the clamping yoke —8— so as to swing about the horizontal axis at right angles to that of the shaft —65— for the purpose hereinafter described.

The yoke —8— is composed of upper and lower sections —87— and —88— engaging the upper and lower faces of an annular flange —89— on the upper end of the post —7—. The upper clamping section —87— fits closely upon the upper end of the tubular post —7— and has a substantially flat lower face resting upon the corresponding upper face of the flange —89— and serves to carry the journaled bearing —86— for the bracket section —83—, while the lower clamping section —88— is loosely mounted around the tubular post —7— and has a convex upper face bearing against the under side of the flange —89— to allow it to adjust itself to different tightening movements of the clamping bolts —90— and —91— by which the clamping yoke —8— with the sectional bracket —9— thereon may be held in any position of angular adjustment about the axis of the shaft —65— or post —7—.

The bearing —86— is split through one side and the clamping bolt —91— is passed through apertures in the opposite walls of the division for the purpose of tightening and releasing the bearing upon and from the hub —85— of the bracket section —83—, thus permitting said bracket section to be turned about an axis at right angles to that of the shaft —65— for varying the angle of the lens-holder relatively to the axis of rotation of the lap —5—, while the swinging movement of the bracket —9— as a whole about the axis of the shaft —65— enables the lens-holder to be moved toward and from the axis of rotation of the lap irrespective of the angle of adjustment of the lens-holder relatively to the axis of the lap.

It is now clear that the clamping bolt —91— controls both of these adjustments and in order that it may be conveniently tightened and loosened, its upper end is provided with a cam lever —92— adapted to be operated by hand and provided with cam faces —93— for engaging similar cam faces on the adjacent face of the bearing —86— as shown in Fig. 10.

The lens-holder as —6— to which the lens —a— may be temporarily secured by any well known fastening means is preferably of considerably less diameter than that of the lap —5— and is provided with a central conical recess —6'— adapted for receiving the pointed bearing member as —94— of an oscillatory operating device by which the lens-holder —6— with the lens

thereon is caused to traverse the surface of the lap.

The bearing member 94 is clamped by means of a bolt 95 to the lower end of an upright rock-shaft 96 which is journaled in suitable bearings in a lateral offset portion on the front end of the bracket section 84 at one side of a reciprocating slide-rod 81 and is provided with a pinion 98 meshing with a toothed rack 99 on the adjacent side of the sliding-rod 81 , whereby the shaft 96 is rocked about its axis and lens-holder 6 is bodily reciprocated or oscillated back and forth in curvilinear paths across the surface of the lap 6 as the rod 81 is reciprocated rectilinearly through the medium of rotary eccentric 73 and pitman 79 .

The bearing member 94 preferably consists of a hardened steel pin pointed at both ends so that either end may be engaged in the recess $6'$ of the lens-holder 6 , while the other end is inserted in one or the other of a plurality of, in this instance two, sockets 100 and 101 in the lower end of the rock-shaft 96 where it is held in its adjusted position by means of a clamping bolt 95 having openings therethrough registering with the sockets 100 and 101 , respectively, for receiving said pin, as shown in Fig. 9 .

One of the sockets as 100 and its corresponding opening in the clamping bolt 95 are disposed at an angle to the axis of the rock-shaft 96 , while the other socket and its corresponding opening in the clamping bolt are parallel with said axis but both of the sockets and their openings are preferably located at opposite sides of the axis of the rock-shaft so as to impart more or less oscillatory motion to the pin and lens-holder as the shaft is rocked in reverse directions, it being understood that when the pin is inserted in the diagonal socket, the lens-holder actuated thereby will be moved through a longer arc than when inserted in the other parallel socket and that the radius of movement may be varied by endwise adjustment of the pin.

In either case, however, the sweep or arc of movement of the bearing pin and lens-holder may be varied by the rotary adjustment of the hand-piece 72 to engage its holding pin 74 in different sockets 75 in the disk 70 by which adjustment the axis of the cylindrical eccentric 73 will be brought closer to or farther from the axis of the vertical shaft 65 .

The bracket section 84 in addition to its rotary adjustment in the bearing 86 about a horizontal axis and its other adjustment about the vertical axis of the shaft 65 is also adjustable vertically rela-

tively to the bracket section 83 for adjusting the pin 94 and its supporting means into and out of engagement with the lens-holder 6 and for this purpose, the adjacent ends of the bracket sections 83 and 84 are provided with dove-tailed connections to enable the section 84 to slide vertically on the section 83 which in turn is provided with an upright toothed rack 102 engaged by a pinion 103 which in turn is journaled in opposite walls of the section 84 and is connected to an external hand-lever 104 whereby the pinion may be rocked in reverse directions along the toothed rack 102 to raise or lower the section 84 as may be desired. A thumb screw 105 is engaged in a threaded aperture in the end of the pinion shaft opposite the hand-lever 104 and is also engaged with the adjacent end wall of the bracket section 84 to hold said section in its adjusted position along the rack 102 .

The bearing member 94 is preferably held in engagement with the tool-holder 6 under yielding pressure and for this purpose, the upper end of the rock-shaft 96 is covered by a cap 106 which is secured by screws 107 to the upper face of the offset portion 97 of the section 84 and is provided with a series of, in this instance four, sockets 108 opening from the lower face thereof for receiving a corresponding number of coil springs 109 having their upper ends bearing against the top wall of the cap 106 and their lower ends engaged with a bearing washer 110 which is loose on the rock-shaft 96 and forms the upper bearing for anti-friction balls 111 , the latter being engaged with an under-lying washer on said rock-shaft, thus permitting the springs 109 to exert continuously downward pressure upon the rock-shaft to hold the pin 94 in engagement with the lens-holder 6 and thereby to yieldingly press the lens against the surface of the lap.

Lubricating system.

As previously stated, the housing 2 is adapted to contain a quantity of oil for lubricating purposes, the various movable parts contained therein being immersed in oil but in addition to this portion of the self-oiling feature is provided an oil pump B secured to and enclosed within the housing and provided at its lower side with an inlet nozzle b and its opposite side with an outlet conduit c leading to the lengthwise channel 26 in the bushing 23 , said pump being of the rotary piston type driven by suitable gearing d from the shaft 19 to draw the oil through the outlet pipe on into the lengthwise channel 26 where it is free to fol-

low along the shaft —22— for lubricating all of the movable parts on said shaft in addition to its bearing in the bushing —23—.

The hollow post —7— is also tightly closed at both ends and serves as a reservoir for oil to lubricate the bearing for the shaft —65—.

It will be noted that practically all of the movable parts are suitably housed in dust-proof casings thereby preventing the entrance of the grinding waste and other materials which may affect the bearings detrimentally.

Operation.

15

The operation briefly stated is as follows:

Assume that the shafts —19— and —61— are being driven continuously from any available source of power and that the clutch controlling lever —49— is forced to its clutch releasing position to enable the collar —41— to operate the clutch levers —37— into frictional engagement with the clutch section —31— for rotating the shaft —22— and lap —5— carried thereby, and that the operating device for the lens-holder has been adjusted to press the lens against the surface of the lap; then the rotation of the shaft —65— will transmit oscillatory motion to the rock-shaft —96— through the medium of the slide-rod —81— and its connections with the eccentric —73— thereby causing the lens-holder —6— to traverse the surface of the rotating lap with a reciprocatory motion.

The lens-holder device may be adjusted toward and from the axis of the lap and also at different angles thereto by simply loosening the clamping lever —92— which loosens the clamping device —8— and splits bearing —86—, thereby permitting the rotary adjustment of the clamping yoke —8— with the bracket —9— thereon about the axis of the shaft —65— and also permitting the bracket —9— to be adjusted rotarily about the axis of the hub —85—, the first adjustment being for the purpose of moving the lens-holder toward and from the axis of the shaft —22—, while the second adjustment serves to bring the lens-holder at the desired angle relatively to the axis of said shaft —22— according to the curvature of the services of the lap —5—, these two adjustments being made to bring the axis of the rock-shaft —96— approximately radial to the arc of curvature of the lap surface.

Rocking the hand-lever —104— up and down will effect the desired pressure toward or release the lens-holder from the lap, aided by the coil springs —109—.

When the grinding or polishing operation is completed, the lever —49— may be shifted to cause the cam —54— to ride up

the roller —53— and thereby to the crank-arm —47— and its shaft —45— upwardly against the action of the springs —56— to release the clutch levers —37— from engagement from the clutch section —31—, thereby stopping the further rotation of the lap while the driving shafts —61— and —19— continue to rotate.

What I claim is:

1. In a lens-surface polishing machine, the combination of a rotary lap, a relatively stationary post parallel with the axis of the lap, a clamping head mounted upon and adjustable rotarily about the axis of said post, a bracket adjustable rotarily upon said clamping head about an axis at substantially right angles to that of the post, a rock-shaft journaled on the bracket, means actuated by the rock-shaft for moving the lens across the surface of the lap, and means for rocking said shaft.

2. In a lens-grinding and polishing machine, the combination of a lap, a lens-holder, a rock-shaft, a bearing-member secured to the rock-shaft at one side of its axis for engaging said lens-holder, a pinion on the rock-shaft, a reciprocatory rack for rocking the shaft, and means for reciprocating said rack.

3. In a lens-grinding and polishing machine, the combination of a lap, a lens-holder, a rock-shaft, a bearing member secured to the rock-shaft at one side of its axis for engaging said lens-holder, a pinion on the rock-shaft, a reciprocatory rack for rocking the shaft, a rotary driving shaft, a pitman connected to the rack, and adjustable connections between said pitman and driving shaft for varying the rectilinear movement of the rack and thereby varying the angular movement of the rock-shaft.

4. In a lens-grinding and polishing machine, the combination of a rotary lap and actuating means therefor, of a lens-holder movable across the face of the lap, a supporting post, a yoke adjustable rotarily upon the post, a bracket adjusted rotarily upon the yoke and composed of sections one of which is adjustable transversely of the axis of rotation of the bracket, a rock-shaft journaled on said transversely adjustable section and provided with a bearing member for engaging the lens-holder, a driving shaft journaled in the post, and means for transmitting motion from the driving shaft to the rock-shaft.

5. In a lens-grinding and polishing machine, the combination of a rotary lap and actuating means therefor, of a lens-holder movable across the face of the lap, a supporting post, a yoke adjustable rotarily upon the post, a bracket adjustable rotarily upon the yoke and composed of sections one of which is adjustable transversely of the axis

- of rotation of the bracket, a rock-shaft journaled on said transversely adjustable section and provided with a bearing member for engaging the lens-holder, a driving shaft 5 journaled in the post, and means for transmitting motion from the driving shaft to the rock-shaft, said means including a pitman adjustably connected to the driving shaft to vary its rectilinear movement.
- 10 6. In a lens-grinding and polishing machine, the combination of a rotary lap and actuating means therefor, of a lens-holder movable across the face of the lap, a rock-shaft having a bearing point at one side of 15 its axis for engaging the lens-holder, a support for the rock-shaft movable toward and from the lap, means including a rack and pinion for adjusting said supporting member and means for operating the rock-shaft.
- 20 7. In a lens-grinding and polishing machine, the combination of a rotary lap and actuating means therefor, of a lens-holder movable across the face of the lap, a rock-shaft having a plurality of sockets at an 25 angle to each other, a bearing member adapted to be inserted in any one of the sockets for engaging the lens-holder, means for clamping the bearing member to the rock-shaft, a support for the rock-shaft, 30 yielding connections between said support and rock-shaft for forcing the latter toward the lap, and means for operating the rock-shaft.
8. In a machine for grinding and polishing lenses, the combination of a rotary lap, 35 a lens-holder movable across the face of the lap, a rock-shaft having a bearing-member for engaging and reciprocating the lens-holder, a pinion on the rock-shaft, a support 40 for the rock-shaft, a toothed rack slideable in said support and engaged with said pinion for rocking the shaft, means for adjusting said support toward and from the lap, a driving shaft and means for transmitting motion from the driving shaft to 45 said rack.
9. In a lens-grinding and polishing machine, a rotary lap-supporting spindle, a rotary lens-operating spindle adjustable lat-
- erally and angularly relatively to the lap- 50 supporting spindle and provided with a pin at one side of its axis for engaging a lens-holder, and means for rocking the second-named spindle in reverse directions.
10. In a lens-grinding and polishing machine, a rotary grinding element, a lens-holder, a rock shaft having a bearing pin adjustable endwise diagonally to the axis of rotation of the rock shaft for engaging and moving the lens in a curved path about said axis across the surface of the grinding element, means for rotating the grinding element, and means for rocking said shaft in reverse directions. 55
11. In a lens-grinding and polishing machine, the combination of a rotary upright shaft, an oil containing housing therefor having bearings for the shaft, a driving shaft extending into the housing, means for transmitting motion from the driving shaft to the upright shaft, an oil pump within the housing having an inlet for receiving the oil and an outlet communicating with one of the bearings, means for transmitting motion from the driving shaft to the pump, a lap mounted in the upright shaft, a lens-holder reciprocally movable across the face of the lap, and means for operating the lens-holder. 60
12. In a lens-grinding and polishing machine, a rotary grinding element, a lens-holder, a rock shaft having a bearing member at one side of its axis for engaging and moving the lens-holder bodily about said axis as the shaft is rocked, supporting means for said shaft adjustable laterally about an axis parallel with that of the grinding element, means for rotating the grinding element at a relatively high rate of speed, and means driven at a relatively low rate of speed for rocking said shaft in reverse directions and thereby to cause the lens-holder to be moved bodily in curvilinear paths across the face of the grinder. 65
- In witness whereof I have hereunto set my hand this 26th day of July, 1921. 70
